David A. Aytell, Genoa N.Y.

80734

Letters Patent March 13, 1834.

The Schedule referred to in these Letters Patent and making part of the same containing a description to the words of the said David A. Aytell himself of his improvement in the mode and manner of making "Horse Power Machines".

To all persons to whom these presents shall come, David A. Aytell of the Village of Genoa in the County of Cattaraugus and State of New York Mechanic, send greeting. Be it known that I the said David A. Aytell have invented constructed and made and applied to use a new and useful improvement in the mode and manner of making Horse Power Machines to be attached to thrashing Machines or any other Machinery called "Aytell's Cast-Iron Horse Power" the whole of the same to be made of wrought or cast iron. The advantage of having the Horse Power and Machinery made of iron, in its being stronger, more durable less liable to go out of order and repair more easily and regular in its operation and altho' of greater strength and power it is of less size more compact, takes up less room, and is more easily transported from place to place, if required, the advantages above recited, the small compass of the machine, the durability of its material the facility with which it can be moved and put in operation its great strength and the power for which it can be obtained gives the said Horse Power a decided advantage and superiority over any other now in use. The Draft of the Horse Power hereto attached and described in plates No. 1, 2, 3, 4, the following thereof together with the Specification and description of the same as given below, particularly set forth and describe the different parts of the machine the distinct operation and use of each part and the effect produced to keep up in operation. The improvement claimed is in making the Horse Power of iron instead of wood or other materials and for the manner in which the same is put together.

Plate C 10. 1

Is an upright right, right hand view of the Horse Power Machine before described as follows. Shows a an upright view of the shaft to which

W.

1. wheel is attached Cog Wheel 60 and 70 by means of a plate of flange cast with and connected to the shaft as represented by 88 in plate Cto. 4. on the top of which is a collar represented by 77 in plates Cto 1 and 2 to which is attached the lever. That more and propels the machine and represented by h. k. in plates Cto 1 and 2 the bottom of the shaft resting on plate 66 and running on a pivot supported at top by plate c. c. and regulated by keeper wedge as represented by letters a. b. b. in plate Cto 4. Letters b. b. The bottom plate from one to two in. -inch thick and 10 inches wide or thereabouts - said plate made permanent and supporting shaft a. at the bottom in which plate the bottom of shaft a. rest in. Thus on a pivot taken in operation said bottom plate being made fast to the foundation as represented by letter e.

c. The top plate supporting shaft a. which more plainly appears in plate Cto 2. letters c. c. the wheel is a traveller or friction wheel which is represented in plates No 1 and 2 and marked letter c. which is rolling on the upper edge of Cog wheel c. c. and 70. regulates the meshing of the Cog of the main wheel (into the cog of pinion wheel f. d. the upright post connecting plate b. b. with plate c. c. as more plainly appear in plate Cto 4 letters a. d. e. the foundation of which the machine is placed f. the pinion wheel meshing into main wheel c. c. 70. on the shaft of which is spur wheel g. as represented by said letter g. in Plates Cto 1. 2 and 3. g. the spur wheel as before mentioned attached to the shaft of pinion wheel f. and meshing into pinion wheel h. as represented by letter h. in plates Cto 1. 2. 3. h. the pinion wheel meshing into spur wheel g. as will plainly appear in plate Cto 3. letter h on the end of the shaft of which is a universal joint connecting with said shaft b. c. c. which when moved propels the machine. i. a small friction wheel or traveller running on top plate c. c. regulating the gearing of main wheel c. c. and 70. into pinion shaft f. j. the collar on top of shaft a. connected as will appear by the top of shaft letters a. in plate Cto 2 to which is attached the lever h. k. in plates Cto 1 and 2. h. k. the lever as before described h. which the power is applied b. b. the two shafts connected by universal joints and vehicle may lay in any angle and connecting the horse power with any other machine in the similar universal joints connecting said shafts b. b. a. a. a. bolt heads or nuts fastening the machine to its foundation through bottom plate b. b. c. c. the body of the machine

wheel as will more plainly appear in plates Cto 2 and 4, and which may be cast whole or in segments or either attached to the shaft, or separate of cast in segments its description will plainly appear by lines y.y.y.y.y.y.y. in plate Cto 4. Letters p.p. the Cog Wheel Cast whole or in segments and attached to the body of the main wheel, a.o. by bolts or screws and nuts. q. Coupling or box in which the shaft runs r. the caps a box or confining the shaft of the machine to the box or places in which it moves as represented by letters r.r.r in plate Cto 2.

Plate Cto 2

C. horizontal view of the top part of the machine. Letter a. the top of main shaft &c. the top plate, d. d. d. Mortises for the uprights or posts as represented by letters d. d. in plate Cto 1. f. g. the Spur wheel as more plainly appears by letters g. g. g. in plate Cto 3. h. the pinion. Notice as will also appear by letter h. in plate Cto 3. i. the Mortises in top plate. c. in which the traveller or friction wheel runs. j. j. j. j. the Collar on top of shaft a. on which rest the levers k. k. k. k. l. k. k. l. k. the levers fastened to collar j. j. j. j. by bolts or screws as represented by square dots. l. the end of the shaft. m. the longitudinal joint o the belly plate of the main wheel cast whole or in segments. r. r. r. the caps a box or confining the shaft to place

Plate Cto 3

C. the upright end view of the Horse Power and Machine. Letter b. the bottom plate. c. the top plate, d. d. the upright posts or pillars. g. g. the Spur wheel meshing into pinion wheel h. k. the pinion wheel.

Plate Cto 4

C. horizontal view of the top of the main Cog wheel. Letter a. represents the manner in which the main shaft, a. in plate Cto 1 passes through the top plate c. in plate Cto 2 and regulated by keys and wedges as represented by letters n. n. n. o. o. o. o. the belly plate of the main wheel cast whole or in segments the segments or divisions being represented by lines y. y. y. y. y. y. 888. the flange or plate cast solid with main shaft a. Plate Cto 1 to which the body of the main wheel is attached by bolts as represented by square dots. The circular dotted line represents the bottom edge of the flange and the line with dots represents the notch in the flange which receives the body of the main wheel. Letters l. l. t. t. t. open spaces in the form of a heart or other shape those t. g. slanting in one end and lessening the weight of the wheel. t. t. t. keys or wedges.

Confining and regulating main shaft in top plate c.c. in plates No 1 and 2.
y 44.4444 Union of segments when body plate of main wheel is cast in segments
and four bolts in plates. Nos 1 and 4, represent bolt heads without by which the
Machine is connected together. Testimony that the above is a true spe-
cification of my said improvement as above described. These prints do not
have this seventh day of May, A.D. 1833, at Genesee County of Ontario and
State of New York.
